ATTORNEY

UNITED STATES PATENT OFFICE.

JOHN W. WARDELL, OF SUGAR, UTAH, ASSIGNOR OF ONE-THIRD TO JOHN STILLMAN
AND ONE-THIRD TO G. WAYNE STILLMAN, BOTH OF SALT LAKE CITY, UTAH.

ELECTROMAGNET SPOOL.

Application filed, January 16, 1925. Serial No. 2,740.

My invention relates to spools on which the insulated wire of electro-magnets are wound, and has for its object to provide a new and economical spool having slotted ends within 5 which slots the end portions of the armature of the magnet are poised, and which ends are laterally and longitudinally shaped to expedite the securing of the pole pieces of the magnet thereto, and to position the said 10 spool ends relative to the pole pieces and the pole pieces relative to the armature.

These objects I accomplish with the device illustrated in the accompanying drawings in which similar letters and numerals of 15 reference indicate like parts throughout the several views and as described in the specification forming a part of this application and pointed out in the appended claims.

In the drawings in which I have shown 20 the best and most substantial embodiment of my invention, Figure 1 is an elevation of one of the spool ends when made of non-insulating material and with lugs for holding the spool from longitudinal movement 25 relative to pole pieces. Figure 2 is an elevation of the end of the spool when the spool is made of insulating material. Figure 3 is an end elevation of the spool when assembled with the pole pieces and armature in place therein. Figure 4 is an edge view of 30 the spool showing the coil wound thereon and the armature in place therein and spaced relative to the pole pieces. Figure 5 is a perspective of the spool core in detail.

In constructing magnet spools and assembling the armature, and pole pieces of an 35 electro-magnet, I have found that much time may be saved and a much better spool may be made if the peripheries of the spool ends are spaced equally from the armature slot, and also when lugs are provided on the periphery of said ends to space the pole pieces 40 relative to the armature.

The present invention consists of the 45 construction and arrangements of parts and combinations thereof as hereafter set out. In the drawings the ends of the spool are shown at A, and which I have given an elliptical form, with segments cut from the top and bottom of their perimeters, as shown at 50 3, and with one or more lugs B extending outwardly, between which lugs the pole

pieces P are placed. An elongated slot C is centrally cut in each spool end A, and the end portions of the armature D are poised 55 in and passed through said slot. The placing of said slot C equally from the upper and lower perimeters of said spool ends aids materially in spacing the armature D equidistant from the pole pieces P, and when so 60 spaced the spool ends A are held firmly in place by the pole pieces P. The core E is stamped out of a flat piece of metal and with recesses 1 cut in each end thereof, and is bent to form a hollow core. The said recesses 1 form an opening through which the 65 assembling and poised of the armature D is conveniently effected. The edges of said core E are soldered to the spool ends A forming a spool. The armature D is poised 70 equidistant from the inside faces of the core E and held in place by the U-shaped wire 2. The wire 2 is soldered to the armature D and to the outside of the spool core E. The insulated wire F is then wound around the 75 spool core E until the necessary amount of the wire required to make the electro-magnet is wound on the core. The pole pieces P are then placed on the sides of the spool and made to bear on the chords 3 of said ends A. When the spool ends A are made of metal a 80 slot 4 is cut from said slot C to the perimeter to prevent the electric current from shorting through the spool ends A. A cheaper form of construction is to make the spool ends A 85 of insulating material, as shown in Figure 2, wherein the slot 4 is omitted. The pole pieces P have flat sides and edges to insure a better fastening of the spool and thereby the desired spacing of the armature. 90

Having thus described my invention I desire to secure by Letters Patent and claim:

1. An electro-magnet spool comprising elliptically shaped end pieces having parallel 95 chord portions on the perimeters thereof, and an elongated slot cut centrally in each end piece and equally spaced from the chord portions of the respective ends; an oblong core in alignment with the slot in said end pieces; an armature poised in said core and extending through the slot in each of said end pieces; with pole pieces between which said spool is closely held. 100

2. An electro-magnet spool comprising tened at its end to the respective spool end end pieces having an elongated slot in each and in alignment with said elongated slot; and segment portions cut away to form two and an armature poised within and fastened 10 spaced apart parallel chords; pole pieces be- to said core.
- 5 tween which said spool is secured and hav- In testimony whereof I have affixed my ing flat sides resting on said chordlike por- signature.
- JOHN W. WARDELL.
